Attorney.

UNITED STATES PATENT OFFICE.

HENRY R. HOLBROOK, OF PUEBLO, COLORADO.

RAILROAD-TIE.

SPECIFICATION forming part of Letters Patent No. 291,514, dated January 8, 1884.

Application filed May 2, 1883. (No model.)

To all whom it may concern:

Be it known that I, HENRY R. HOLBROOK, a citizen of the United States, residing at Pueblo, Colorado, have invented new and useful 5 Improvements in Railroad-Ties, of which the following is a specification.

My invention relates to certain new and useful improvements in railroad ties.

It has for its object to provide a tie composed 10 of any suitable metal and of tubular or equivalent form in cross-section, strengthened and reinforced at such points as are subjected to the crushing effects of the passing rolling-stock, and at the same time to preserve lightness and 15 economy of material in the structure as a whole.

My invention consists of a metallic railroad-tie of tubular or equivalent form in cross-section, and sufficiently strong throughout its entire length to hold the two rails when secured 20 thereto firmly to true gage, and provided with a re-enforce at such points as are necessary to resist the crushing effects of passing trains, as will be hereinafter fully explained.

25 In order that others skilled in the art to which my invention appertains may fully understand the same, I will proceed to describe its construction and operation, referring by letters to the accompanying drawings, in which—

30 Figure 1 is a longitudinal section of a tie embodying my invention; Fig. 2, an end view of the form shown at Fig. 1; Fig. 3, a longitudinal section, showing a modification of the form shown at Fig. 1; Fig. 4, an end view of 35 the form shown at Fig. 3; Fig. 5, a longitudinal section of still another modification, and with the rails secured in place on the tie by the usual chairs and bolts; and Fig. 6 is an end view of the form shown at Fig. 5 without the 40 rails, &c.

Similar letters denote like parts in the several figures.

The tie is made of rolled iron or steel of the form in cross-section shown. At the points A 45 A the metal is thickened up, to form a re-enforce to receive the rails and sustain the crushing effect of the rolling-stock passing over them. These thickened portions are of course made with reference to the desired gage of the 50 road, and extend entirely around the whole circumference of the tie. Between said re-enforces, and for a suitable distance each side

thereof, the tie is reduced, as clearly shown, to about one-fourth the thickness of said re-enforces, so that the proper economy of metal 55 is secured, while at the same time sufficient strength is preserved to tie the rails in proper gage adjustment and to furnish suitable bed-contact.

It will be understood by reference to Figs. 60 1, 3, and 5 that the re-enforcements may be on the outside, partially outside and inside, or entirely inside, without departing from the spirit of my invention.

In order to be able to secure the rails in position on the ties, the latter are provided at suitable points with bolt-holes, and chairs are rigidly fixed in place by bolts, as clearly represented at Fig. 5.

I propose making my improved tie either 70 by casting or rolling in any manner which may be most desirable or that may be hereafter suggested.

I am aware that it is not broadly new to make a railroad-tie of iron, and that it is not 75 new to make a tubular tie with raised or flat seats at each end to receive and support the rails, and do not wish to be understood as making any such broad claim, the gist of my invention resting in the idea of a metallic tie 80 of tubular or equivalent form in cross-section, the major parts of it being as light as possible, and that portion over which the rails are designed to run, and which receives the crushing effect of the rolling-stock, being strengthened 85 by a re-enforce extending uniformly around the tie.

What I claim as new, and desire to secure by Letters Patent, is—

A tubular metallic railroad-tie of elliptical 90 or equivalent form in cross-section, provided at the points over which it is designed to secure the rails with re-enforcements A A, extending uniformly around the circumference, whereby sufficient strength with the minimum 95 degree of weight is secured, substantially as hereinbefore set forth.

In testimony whereof I have hereunto set my hand in the presence of two subscribing witnesses.

HENRY R. HOLBROOK.
